DISPLAY CARD FOR PACKAGED MERCANDISE

Harold Katz, Jericho, N.Y., assignor to Empire Brushes,
Inc., Port Chester, N.Y., a corporation of New York

Filed Apr. 14, 1967, Ser. No. 6,705

Term of patent 14 years

(Cl. D9—191)

FIG. 3

FIG. 1

FIG. 1 is a top plan view of a display card for packaged merchandise embodying my new design;

FIG. 2 is a side elevational view thereof;

FIG. 3 is a top plan view of a modified form of a display card for packaged merchandise shown in FIG. 1; and

FIG. 4 is a side elevational view of FIG. 3.

I claim:

The ornamental design for a display card for packaged merchandise, substantially as shown and described.
